INVENTOR.

UNITED STATES PATENT OFFICE

2,283,157

TRANSLATION OF MODULATED ELECTRIC CURRENT INTO A SERIES OF IMPULSES

Maynard D. McFarlane, Hollywood, Calif.

Original application June 3, 1926, Serial No. 113,432, now Patent No. 2,070,913, dated February 16, 1937. Divided and this application August 21, 1936, Serial No. 97,203. In Great Britain April 1, 1926

25 Claims. (CL. 178—7.1)

This invention relates to the conversion of a modulated electric current into a series of impulses; and this application is a division of my application Serial No. 113,432 filed June 3, 1926, now patent No. 2,070,913, issued Feb. 16, 1937.

The invention will be described with particular reference to a system of transmitting pictures, writing or the like, but it will be understood that the invention in its broadest aspect is not restricted to this particular embodiment, the application of the invention to the sending of pictures being chosen by way of an illustrative example and being one in which actual use is being made of the invention with very satisfactory results especially as to the quickness and ease of transmission, since it is thereby made possible to transmit pictures or the like by electrical impulses in the form of a message as transmitted in standard telegraphic practice.

In systems of telephotography it is generally necessary to form a reproduction of the representation to be transmitted and such systems have been proposed in which light transmitted through a negative has been caused to modulate the current flow in an electrical circuit, other apparatus being operated by these modulated signals to re-constitute the original representation.

Other and comparatively complicated systems have been proposed according to which electrical impulses of intensity governed by the graduations of a photographic negative have controlled sources of light of different power in order to reproduce a pictorial image of the original. Systems of the type referred to have not, as far as we are aware, achieved any considerable success owing to draw-backs inherent in the methods employed. These draw-backs were substantially overcome by the system of telephotography described in our prior British Patent No. 197,402 according to which an intermediate record of the original was made in the form of a perforated tape preferably employing the 5-unit or Baudot code. While this method of transmission obtains very satisfactory results the extra apparatus required to make the intermediate record at either or both ends of the transmission line is not essential where a private line is available.

The general object of the invention is to provide a method of converting a modulated electric current into a series of impulses, which impulses may be employed for a variety of purposes of which a particular example is hereinafter given by way of illustration of the application of the

invention. It is to be understood, however, that the utilization of said impulses derived from the modulated electric current is applicable to a wide variety of uses and is in no way limited to the specific application described.

A feature of the invention is the application of a modulated electric current converted into a series of impulses, according to my invention, to the transmission of a picture or other representation of an original. This can be effected with or without the formation of an intermediate record.

With the above object in view the invention may embody a method of controlling an electrical system whereby a modulated electric current is transformed into a series of impulses, said method comprising impressing upon an electric current fluctuations caused by modulations due to an exciting cause and means transforming said modulated current into a series of impulses which may be utilized for any desired purpose.

Also, the invention may embody a method of controlling an electrical system in which fluctuations representing variations of an original are impressed upon the electric current and the series of impulses obtained are utilized to produce a representation of said original.

Further, the invention may embody a method in which light is thrown upon a pictorial or other representation and the tones thereof interpreted by the varying amount of transmitted or reflected light, said light acting to modulate the electric current which is transformed to produce a series of impulses.

The invention may also include transforming the modulated current obtained by the method set forth in the preceding paragraph into a series of telegraphic impulses by the use of relay means.

The invention also contemplates a method of pictorial or other transmission, comprising employing a negative or print of a representation to control light sensitive modulating means acting to impress fluctuations corresponding to the amount of light transmitted or reflected by said negative or print upon an electrical current flowing in a circuit and transforming said modulating current into a series of impulses adapted to be utilized in forming a reproduction of said representation.

The invention further comprises apparatus for controlling an electrical system comprising modulating means adapted to be acted on by fluctuations desired to be registered, said fluctuations being impressed upon said system by said modu-

lating means and means acting to transform the resulting modulated current into a series of impulses.

The invention further comprises apparatus as set forth in the preceding paragraphs in which said impulses are utilized to control means acting to record said variations.

The invention still further comprises apparatus for controlling an electrical system by modulating means in the form of a light sensitive element such as a photo-electric cell, and means for impressing said fluctuations upon said system and transforming the modulations into a series of impulses.

Further features of the invention will herein-after appear and be specifically pointed out in the appended claims.

The accompanying drawing is a schematic diagram showing apparatus which may be used in carrying out the present invention.

In the figure, 1 represents a picture or other subject to be transmitted, mounted upon a cylinder 2, which is mounted upon a shaft 4 rotatable by a suitable gearing arranged in the gear case 5. The shaft 4 is provided with a thread, and under control of the gearing in the gear case 5, the rotation of said shaft rotates and laterally feeds the picture across the path of a pencil of light projected onto the surface of the picture by a suitable source of illumination arranged in the casing 6; the light controlled by the characteristics of the picture or other subject 1, then being reflected and falling upon the photo-electric cell 7.

Suitable optical systems, indicated in the diagram by lenses 8 and 9, may be arranged to focus the light spot on the surface of the picture and to collect the light reflected.

It has heretofore been proposed to use a photographic transparency of the original to be transmitted, and to shine a beam of light through this transparency, utilizing the light transmitted by a small area to energize the photo-electric cell. While this form of analyzing means gives satisfactory results, I prefer to use the arrangement of the apparatus illustrated, in which the picture or other subject to be transmitted is in the form of a print mounted upon a cylinder; and the light reflected from the surface thereof influences the photo-electric cell 7. This arrangement possesses considerable advantage over the arrangement employing the transparency since it is not necessary to prepare a transparency for the purpose of transmitting the picture.

A further modification of the analyzing means (not illustrated) which may have advantages in particular circumstances, is to employ a beam of light in place of the focused pencil in the arrangements just described, the light reflected from a point within the illuminated area being directed by a suitable lens system upon the photo-electric cell.

As shown in the drawing, the pencil of light is directed onto the picture at one angle and the photo-electric cell receives light reflected at a different angle, which adapts the apparatus for efficient and satisfactory operation with glossy prints as well as with mat prints.

The photo-electric cell is caused to modulate electric current; and in the form of the invention shown in the drawing, the modulated current operates perforating mechanism, which may be of any suitable character. This is done through a bank of relays 10a, 10b, 10c, 10d and 10e, individually adjusted by variable resistances

11a, 11b, 11c, 11d and 11e. For the sake of convenience, the perforating mechanism may be used for producing a tape adapted to be utilized in a standard five unit transmitting machine.

5 The current flowing through the photo-electric cell is amplified by any suitable means, but preferably by the use of electronic valve devices, such as 3-electrode amplifiers, and one suitable circuit is here described. The photo-electric cell is connected in the grid circuit of the electronic valve device, for instance a pair of 3-electrode tubes, as will be understood by those familiar with amplification with these devices. The current flowing in the circuit is a current which may be of any 10 suitable kind as D. C. or one having a varying value of a constant characteristic such as a pulsating current; the latter form is convenient in that the usual transformer devices may be utilized for voltage amplification. Current may of course be supplied from any suitable source, as for instance a direct current generator or a source of direct current used in conjunction with suitable means such as a mechanically operated commutator, a buzzer, or an oscillator tube to transform continuous into intermittent current.

15 The photo-electric cell 7 is shown connected to the grid of the 3-electrode amplifier tubes 14 and 15; 16 representing the battery for the photo-electric cell and 17 the battery for the plate of the amplifier; 18 is the bias battery and 20 is the filament battery for the tubes 14 and 15. While conventional batteries are shown in this circuit, it is to be understood that they may be replaced by any other suitable source of power, as above indicated.

20 While I generally prefer to employ a grid leak 18 as shown, it will be understood, of course, that amplifying circuits without a grid leak and biasing battery can be employed; for instance very satisfactory amplification has been obtained from 25 a circuit in which neither a grid leak nor biasing battery are utilized, although in this case careful adjustment of the voltages applied to the photo-electric cell and amplifying tube or tubes is required.

30 It will further be understood that when a pulsating current is used, means supplying the interrupted current may be positioned in any suitable part of the circuit and not necessarily before the first amplifying tube and further it will be understood that any suitable arrangement or number of amplifying tubes may be employed; for instance satisfactory results have been obtained from two or three amplifying tubes arranged in parallel as well as from a number of tubes arranged in straight cascade formation. It will be observed that the tubes shown in the circuit arrangement are supplied by a common lead. In the case of a pulsating current modulated by the photo-electric cell, or a series of pulsating light impulses, the amplification may of course be by any suitable means such as transformers, resistance coupling, capacity coupling and the like.

35 The output circuits of the tubes 14 and 15 may be applied to a bank of relays to control the operation of the perforated mechanism serving to render the analyzed picture or the like into a perforated tape of the five unit or Baudot code as used in standard telegraphic practice.

40 The schematic arrangement of such an output circuit is illustrated. The relays 10a, 10b, 10c, 10d and 10e are conveniently of the polarized type, and the relays shown are of the type known as the "British post office relay." The

Operating windings of these relays are shown connected in series in the plate lead of the tubes 14 and 15. Thus the current from the batteries 17 passes through the operating windings of the relays 10a, 10b, 10c, 10d and 10e in sequence and thence to the plates of the tubes 14 and 15. Thus, the fluctuations of current caused by the light sensitive element 7 are impressed upon the grids of the amplifying tubes 14 and 15, and the amplified current reproducing these variations flows through the coils of all the relays 10a, 10b, 10c, 10d and 10e causing corresponding variations in the electro-magnetic pull exerted on the tongues of said relays.

Each relay 10a, 10b, 10c, 10d and 10e has its restraining or biasing winding connected to a source of current 21 through appropriate adjustable resistances 11a, 11b, 11c, 11d and 11e, in such a manner that the biasing current to the relay 10a is controlled by the setting of the resistance 11a, that of 10b by the resistance 11b etcetra. The setting of the resistance 11a therefore controls the current necessary in the operating winding of the relay 10a to operate it, and similarly the operating current for the relay 10b is controlled by the resistance 11b, and so on.

It is found that by this arrangement of control means, the relays may be very readily set for different values of operating current. It will be understood that it is impractical to permanently adjust the relays since each picture, to obtain the best results, should be analyzed into tones depending on the range of tone of the picture. For instance suppose a print is being used at 1 and the amount of variation in the operating current is twenty milliamperes, effected by the current ranging from forty to sixty milliamperes, it might be possible to obtain satisfactory rendition of the tones with relays set to operate at differences of four milliamperes, i. e. to operate at forty-four, forty-eight, etc. milliamperes. However, the density of the shades of a negative or print are a logarithmic function of the light received by the film on taking the photograph, and conversely. Obviously, therefore, an arithmetical progression of increase of current would not cause the relays to operate in true manner. Apart from this feature, however, there is an inherent difference in the character of the pictures to be transmitted. It might also be desired to vary the tones of the reproduction from those of the original; and it is a very important feature that this effect is readily obtained by the adjustment of the relays, as for instance to arrange them in a series operating on currents of forty, forty-six, fifty-one, fifty-eight and sixty milliamperes. The improved control over the tone grading of the picture transmitted is, it will be realized, a very important feature of the invention.

The tongues of the relays 10a, 10b, 10c, 10d and 10e are adapted to close circuits through individual selector magnets, of which only one 12a is shown in the drawing. Thus current from the source 13 flows through the contacts of the relays and the appropriate tongues thereof to cause the selection of the code combination to be perforated in the tape. The perforating mechanism itself is shown in the above mentioned British Patents Nos. 197,402 and 195,577.

In the embodiment of the invention herein discussed, the perforation of a standard telegraphic tape to render five tones has been described. It is understood, however, that the invention is not in any way limited to the number of tones

rendered or to the employment of a standard form of perforated tape, since even when using such a tape it is possible to render 32 tones. Five tones have been found generally satisfactory for commercial use or possibly a smaller number of tones might serve the purpose required (as when transmitting a black and white drawing, signature or the like), but on the other hand a larger number of tones might be desirable when rendering the tones of a very delicately shaded subject.

It will also be realized that for ease in transmission, the standard telegraphic tape is generally suitable and convenient. An intermediate record produced need not be in the form of such a tape, some other form of record having perhaps special value in connection with some particular method of reproductions of a representation.

It is desired to point out that where the mechanism so far described is used to operate a perforator of standard type by which a standard perforated tape is produced, the tape may be utilized either for forming a direct reproduction of the transmitted picture or for sending signals, with which to operate a similar perforating mechanism at the receiving station to form a duplicate perforated tape; and it is of course feasible to send a picture analyzed into impulses directly to a receiving station (without forming the intermediate record) and use these signals to effect the reproduction of the representation transmitted.

Whenever standard forms of polar relays are used the operation of such relays may be improved in various ways. It is well known that the operation of such relays in telegraph circuits is improved by the use of vibratory circuits which have become standard. These standard vibratory circuits can be more or less directly applied to the circuits herein described. Alternatively the action of the relays may be improved by passing weak alternating current through one or more windings of the relay, for instance, through the vibrating winding thereof, or again, weak alternating current of suitable frequency may be super-imposed in any suitable manner on the operating or biasing currents of the said relays.

Another possible method for improving the operations of the relays is to supply one or more of the windings of the relays with pulsating current, for instance, by inserting an automatic make-and-break in the biasing winding or in the common return of a bank of relays; and the speed of the make-and-break is preferably timed to have a definite ratio to the speed of operation of the punching mechanism, as for instance, by being operated by said punching mechanism.

It is believed that the operation of my invention will be readily understood and further explanation is not therefore considered necessary, but a short summary thereof may be stated as follows:

The current flowing in a circuit, such as a direct current or interrupted current, is modulated by suitable means acting to render tones or variations desired to be registered and the modulated current is transformed into a series of impulses. These impulses (telegraphic or other) are used to operate suitable mechanism.

Where in the appended claims I have referred to a picture, it is understood that reference is made to an original subject which is to be transmitted; this original subject may be in the form of a picture, photograph, drawing, printed mat-

ter, or any other subject of which it is desired to produce a replica at a receiving station.

Where I have referred to unit areas or elemental areas of a picture or subject to be transmitted, it is to be understood that these terms refer to the elements into which the picture or other subject is resolved for purposes of transmission. These elemental or unit areas are all of the same size and shape; the size being determined by the amount of optical resolution to be achieved. The system of picture transmission therefore consists in the transmission from a sending to a receiving station of a series of signals, each one of which corresponds to one of the areas into which the original subject has been resolved by the scanning means.

Having now described my invention, I claim:

1. In a picture transmission system in which the line current transmitted to a receiving station is varied so that the variations in said line current shall correspond to the varying tone value of successive elemental small areas of a picture or the like which is to be transmitted, means for causing a pencil of light whose intensity varies with the tone value of the successive small areas to produce an electric current of corresponding varying intensity, a plurality of relay devices selectively operable in accordance with the intensity of said current, and an adjustable resistive element for controlling the biasing current for at least one of said relay devices.

2. In a picture transmission system, in which the line current transmitted to a receiving station is varied so that the variations in said line current shall correspond to the varying tone value of successive elemental small areas of a picture or the like which is to be transmitted, means for causing a pencil of light whose intensity varies with the tone value of the successive small areas to produce an electric current of corresponding varying intensity, a plurality of polarized adjustable relays selectively operable in accordance with the intensity of said current, and means for controlling the biasing current of said relays.

3. In a picture transmission system, in which the line current transmitted to a receiving station is varied so that the variations in said line current shall correspond to the varying tone value of successive elemental small areas of a picture or the like which is to be transmitted, means for causing a pencil of light whose intensity varies with the tone value of the successive small areas to produce an electric current of corresponding varying intensity, a plurality of polarized adjustable relays selectively operable in accordance with the intensity of said current, and means for controlling the biasing current of said relays, said means including a plurality of adjustable resistances.

4. In a picture transmission system, means for causing a pencil of light whose intensity varies with the tone value of successive elemental small areas of a picture or the like to be registered to produce electric impulses of corresponding varying intensity, a plurality of separate electric circuits adapted to be energized at varying impulse intensities, and means for setting said electric circuits to select and render the varying intensity impulses into telegraphic impulses of substantially constant intensity and varying duration.

5. In a picture system, in which the line current transmitted to a receiving station is varied so that the variations in said line current shall correspond to the varying tone value of suc-

sive elemental small areas of a picture or the like which is to be transmitted, means for causing a pencil of light to be reflected from the surface of said picture to produce an electric current of varying intensity corresponding to the tone value of successive small areas, a plurality of relay devices selectively operable in accordance with the intensity of said current, and an adjustable resistive element for controlling the biasing current for at least one of said relay devices.

6. In the art of telautography, that step in the art which consists in causing a beam of light to be reflected from a picture which is to be transmitted and causing said reflected beam of light to produce an electric pulse of intensity corresponding to the tone value of a unit area of said picture.

7. In the art of telautography, those steps in the art which consist in causing a beam of light to be reflected from a picture which is to be transmitted, causing said reflected beam of light to produce an electric pulse of intensity corresponding to the tone value of a unit area of said picture, and causing said electric pulse to directly control the line circuit.

8. In the art of telautography, those steps in the art which consist in causing a beam of light to impinge on a picture which is to be transmitted and causing light reflected from a unit area of the surface of said picture to produce an electric pulse of intensity corresponding to the tone value of said unit area.

9. In the art of telautography, means to cause a beam of light to impinge on the surface of a picture which is to be transmitted, and means for applying light reflected from a unit area of said surface at an angle other than the angle of said beam to cause the production of an electric pulse of intensity corresponding to the tone value of said unit area.

10. In the art of telautography, means to illuminate successive elemental areas of the surface of a picture which is to be transmitted, and means for producing electric pulses by light non-specularly reflected from said elemental areas of the surface, the pulses corresponding to the tone values of the elemental areas.

11. In the art of telautography, means to illuminate successive elemental areas of a picture which is to be transmitted, means to produce electric pulses by light non-specularly reflected from said elemental areas of the surface of said picture, the pulses corresponding to the tone values of said elemental areas, and means for amplifying said pulses to produce a signal for the production of a representation of said picture.

12. In a picture transmission system, means to pass successive small areas of a picture which is to be transmitted before a scanning mechanism, and means for causing non-specular reflections from the succession of unit areas to produce a succession of electric pulses of value corresponding to the tone value of said unit areas.

13. In a picture transmission system, means to pass successive small areas of a picture which is to be transmitted before a scanning mechanism, means for causing non-specular reflections from the succession of unit areas to produce a succession of electric pulses corresponding to the tone values of the unit areas, and means for producing a representation of said picture.

14. Apparatus pertaining to the transmission of pictures comprising: a source of light, means to establish a beam of light from said source,

means to advance a picture relative to the beam to cause successive elemental areas thereof to influence the beam of light, means to produce an electric current by non-specular reflection from the picture, and means to select circuits corresponding to the intensity of the reflected light.

15. Apparatus pertaining to the transmission of pictures comprising: a source of light, means to establish a beam of light from said source, means to advance a picture relative to the beam to cause successive elemental areas thereof to influence the beam of light, means to produce and amplify an electric current proportional to the intensity of the light reflected from said elemental areas, and means including a bank of polarized adjustable relays for the selection of circuits corresponding to the tone values of said elemental areas.

16. Apparatus pertaining to the transmission of pictures comprising: a photo-electric cell, means to pass elemental areas of a picture or the like before said cell, means to illuminate said elemental areas and to produce an electric current in said cell corresponding to the intensity of non-specular reflection of the light from said succession of elemental areas.

17. Apparatus pertaining to the transmission of pictures comprising: a photo-electric cell, means to pass elemental areas of a picture before said cell, means to illuminate said elemental areas and to produce an electric current in said cell corresponding to the intensity of non-specular reflection of the light from said succession of elemental areas, and apparatus to amplify the output of said photo-electric cell.

18. In a picture transmission system a scanning mechanism comprising means to illuminate a picture which is to be transmitted and means to collect non-specularly reflected light from the surface of said picture and influence an electric circuit thereby to produce electric currents in said circuit corresponding to the tonal intensities of said elemental areas.

19. In the method of electrically transmitting pictures, those steps which comprise: illuminating a photo-responsive device by diffuse reflection from a succession of elemental areas of a picture to be transmitted, and producing therefrom a succession of electric impulses related individually to the visual tonal intensities of the corresponding elemental areas of said picture.

20. In a picture transmission system, an original subject which is to be transmitted, means for illuminating an elemental area on said subject, and means for causing the diffuse reflection from said area to control the amount of current flowing in a circuit.

21. In a picture transmission system, an opaque picture to be transmitted, a photo-responsive device, a source of light, and means to produce a

succession of electrical impulses in said photo-responsive device through the agency of light from said source reflected from said picture, the said impulses corresponding to the tonal values of successive small elemental areas of said picture.

22. In a picture transmission system wherein a succession of signals corresponding to the tonal values of a succession of elemental areas of a picture is transmitted from a sending station to a receiving station, a picture, a source of light, means to illuminate an elemental area from said source, a photo-electric device adapted to be influenced by light reflected from said area, means to cause a relative movement between said picture and said source of light and said photo-responsive device to scan a succession of similar elemental areas, and circuit means controlled by the photo-electric device for the production of said transmitted signals.

23. In a picture transmission system a transmitting cylinder, an original subject which is to be transmitted mounted on said cylinder, means to rotate said cylinder, an optical system, means to scan the original subject on said cylinder with said optical system; a light sensitive element in said optical system, means to activate said light sensitive element by light reflected from said original subject on said cylinder, and means to produce under the control of said light sensitive element signals corresponding to the tonal values of individual unit areas of said original subject.

24. In a picture transmission system a transmitting cylinder, an original subject which is to be transmitted mounted on said cylinder, means to rotate said cylinder, an optical system, means to scan the original subject on said cylinder with said optical system; a photo-electric cell in said optical system, means to activate said photo-electric cell by light diffusely reflected from said original subject on said cylinder, and means to produce under the control of said photo-electric cell signals corresponding to the tonal values of individual unit areas of said original subject.

25. In a picture transmission system in which the line current transmitted to a receiving station is varied so that the variations in said line current shall correspond to the varying tone value of successive elemental small areas of a picture or the like which is to be transmitted, means for causing a pencil of light whose intensity varies with the tone value of successive small areas to produce an electric current of correspondingly varying intensity adapted to operate a plurality of relay devices selectively operable in accordance with the intensity of said current, and adjustable means for controlling the relay selection in response to a predetermined picture current intensity.

MAYNARD D. McFARLANE.
